CLAIM

The ornamental design for an oval light fixture frame and lens therefor, as shown and described.

DESCRIPTION

FIG. 1 is a top view of an assembly of an oval light fixture frame and lens therefor embodying my new design;

FIG. 2 is a front view thereof, the rear view being identical thereto;

FIG. 3 is a left side view thereof;

FIG. 4 is a right side view thereof;

FIG. 5 is a top, front and right side isometric view thereof;

FIG. 6 is a top, front and left side isometric view thereof;

FIG. 7 is a bottom view thereof;

FIG. 8 is a bottom, front and right side isometric view thereof;

FIG. 9 is a bottom, front and left side isometric view thereof;

FIG. 10 is a top view of the frame without the lens;

FIG. 11 is a front view of the frame without the lens;

FIG. 12 is a left side view of the frame without the lens, the right side view being a mirror image thereof;

FIG. 13 is a top, front and right side isometric view of the frame without the lens;

FIG. 14 is a top, front and left side isometric view of the frame without the lens;

FIG. 15 is a bottom view of the frame, this view being identical to FIG. 7;

FIG. 16 is a bottom, front and right side isometric view of the frame;

FIG. 17 is a bottom, front and left side isometric view of the frame;

FIG. 18 is a top view of the lens;

FIG. 19 is a front view of the lens, the rear view being identical thereto;

FIG. 20 is a right side view of the lens;

FIG. 21 is a left side view of the lens;

FIG. 22 is a top, front and left side isometric view of the lens;

FIG. 23 is a top, front and right side isometric view of the lens;

FIG. 24 is a bottom view of the lens;

FIG. 25 is a bottom, front and right side isometric view of the lens; and,

FIG. 26 is a bottom, front and left side isometric view of the lens.
